UNITED STATES PATENT OFFICE

103,734

DESIGN FOR A TEXTILE FABRIC OR SIMILAR ARTICLE

James Mohan, Somerville, Mass., assignor to Fairclough & Gold, Inc., Boston, Mass., a corporation of Massachusetts

Application February 8, 1937, Serial No. 67,501

Term of patent 3½ years

To all whom it may concern:

Be it known that I, James Mohan, a citizen of the United States, residing at Somerville, in the county of Middlesex and State of Massachusetts, have invented a new, original, and ornamental Design for a Textile Fabric or Similar Article, of which the following is a specification, reference being had to the accompanying drawing, forming part thereof.

The figure is a plan of a textile fabric or similar article showing my new design.

I claim:

The ornamental design for a textile fabric or similar article, as shown.

JAMES MOHAN.
